UNITED STATES PATENT OFFICE

2,690,368

FOLDING TABLE WITH SPRING LEAF LOCK

Alfred A. Troyke, Amelia, Ohio

Application May 3, 1952, Serial No. 285,854

1 Claim. (Cl. 311—88)

1

This invention relates to folding tables and more particularly, to folding tables that can be stored as a group in a cabinet and to a cabinet for storing same.

An object of this invention is to provide a folding table having cantilever-mounted springs for holding the legs in an upright or table top supporting position.

A further object of this invention is to provide means for adjusting such springs so that the legs are firmly held in table top supporting position.

The above and other objects and features of the invention will in part be apparent and will in part be obvious from the following detailed description, and the drawing, in which:

Figure 1 is a bottom plan view of a table constructed in accordance with an embodiment of this invention, the legs of the table being folded flat against the top thereof;

Fig. 2 is a view in lengthwise section of the table showing the legs in raised position;

Fig. 3 is a view in section taken along a line III—III of Fig. 1;

Fig. 4 is an enlarged fragmentary view in section showing details of the leg holding mechanism of the table; and

Fig. 5 is a perspective view showing a cabinet for storing tables with tables stored therein.

In the following detailed description, and the drawing, like reference characters indicate like parts.

As shown in Figs. 1 and 2, a table 10 constructed in accordance with an embodiment of this invention, includes a table top 11 and folding legs 12. Top 11 may be flat and rectangular in shape. A downwardly projecting peripheral or border flange 13 is attached to the under side of table top 11. The flange 13 receives hinge pins 14 by means of which the legs 12 and leg connecting cross members 16 are hinged to the under side of the table top at opposite ends thereof. Each cross member 16 carries a pair of legs 12. The legs swing with the cross members from a folded position shown in Fig. 1, to an upright or table top supporting position shown in full lines in Fig. 2. When each pair of the legs is in upright or table top supporting position, the cross member 16 attached thereto is in engagement with flange 13. The flange 13 limits the distance the legs can swing outwardly, as shown in Figs. 2 and 9.

The legs are held in table top supporting position by cantilever springs 17. As shown, each of the cross members is provided with a notch 18 for receiving the free end of one of the canti-

2

lever spring members 17 adjacent thereto. The fixed ends of the cantilever spring members are attached to a block 21 which is firmly attached to the under side of the table top 11. Each spring member is attached to block 21 by means of releasable screws 22. Screws 22 pass through slots 23 (see Fig. 3) in the springs. When the screws are released, the spring members can be moved toward or away from each other. As shown in Fig. 1, the spring members are in alignment and adjacent ends thereof are closely spaced, so that, when one or both of the spring members is released, a screw driver blade can be inserted between the spring members and turned to drive them apart to proper position. When the spring members are properly positioned, screw 22 may be tightened to hold the spring members firmly in place.

As shown in Fig. 2, the free end of each spring 20 is adapted to engage the notch of the adjacent cross member 16 to hold the assembly of cross member and legs carried thereby in upright position. When each assembly is in upright position, the cross member thereof bears against border flange 13 to prevent swinging of the leg members away from beneath the table top, as already pointed out. The springs are adjusted so that, when the cross members are firmly in engagement with flange 13, the ends of the springs engage outer walls 23 of the notches.

30 The spring members and the cross member may be formed of wood. As the wood wears with use, the springs may be periodically adjusted so that, notwithstanding wear of springs and cross members, the legs can at all times be held firmly in upright position.

When the leg members are to be folded flat, each spring is raised to the position indicated in dot-dash lines at 17a in Fig. 2, whereupon each cross member and leg assembly can be swung to the position indicated at 12a in Fig. 2. In this position the spring rests on the face 23' (Fig. 4) of the cross member. When each leg assembly is further swung toward the table top, the spring associated therewith urges the leg assembly to the position shown in Fig. 1, in which the leg members and the cross member are flatwise against the table top and the spring bears on face 24 (Fig. 4) of the cross member.

50 As shown in the drawing, the leg members and cross members are so formed, that, when folded flat, as indicated in Fig. 1, the leg members and cross members are inside peripheral flange 13. Each cross member is spaced from one of the 55 sides of the table by a block 25 so that the legs

are offset from each other and rest against the under side of the table top 11.

The table 10 and a plurality of other similar tables may be stored in a cabinet 26. Cabinet 26 includes a storage space 28 having side walls 29, a back wall 31, and front doors 32. The top and bottom walls of cabinet 26 are formed by corrugated members, each of which includes spacer blocks 34 between which are formed grooves 36. The grooves of the upper corrugated member are directly above the grooves of the lower corrugated member to form pairs of grooves or slide ways for receiving the tables. Each table is slid into place in one of the pairs of grooves of the cabinet so that a plurality of tables can be stored in the cabinet in side by side relationship.

The tables and cabinet described above and illustrated in the drawing are subject to structural modification without departing from the spirit and scope of the appended claims.

Having described my invention, what I claim as new and desire to secure by Letters Patent is:

A folding table which comprises a substantially rectangular table top, spaced U-shaped leg units hinged to the underside of the table top at opposite ends thereof, each leg unit comprising a cross member and a leg member attached to each end of the cross member, a downwardly projecting flange on the underside of the table top adjacent to each cross member, each leg unit being swingable between a raised position in which the legs are substantially perpendicular to the table top and the cross member engages the flange adjacent thereto and a lowered position in which the legs are flatwise against the underside of the table top,

there being a spring-receiving seat on the cross member of each leg unit, a pair of aligned cantilever leaf springs, means for releasably attaching the springs to the underside of the table top between the cross members and extending at right angles to the cross members, the free ends of the springs engaging the spring-receiving seats of the cross members when in table top supporting position with the free ends of the springs in engagement with the seats to lock the leg units in that position and against the flanges, the attached ends of the springs being closely spaced, whereby, when the springs are released, a tool can be inserted between the closely spaced ends of the springs to urge the springs apart and to a position where the free ends of the springs firmly engage the seats to hold the cross members of the leg units firmly against the flanges.
